J. R. SHOWERS

UNIVERSAL CASH DRAWER CABINET FOR REGISTERS

Filed July 14, 1924

UNITED STATES PATENT OFFICE.

JOSEPH RALPH SHOWERS, OF SHELBYVILLE, INDIANA.

UNIVERSAL CASH-DRAWER CABINET FOR REGISTERS.

Application filed July 14, 1924. Serial No. 728,029.

This invention relates to a cash drawer containing cabinet which is adapted to be independently associated with substantially all present commercial makes of registers and detachably support the same and be simultaneously operable with and by the operating element of the register. This application is a continuation in part of my copending application, Serial No. 412,694, filed September 25, 1920. The form of the invention disclosed herein is the preferred specific form of the generic invention which is common to this form and that disclosed in the copending application.

15 The chief object of the invention is to construct a latching mechanism that is universally and readily adjustable to any operating member of substantially any one of all the present commercial registers, where- 20 by the combination of the cash drawer, cabinet and the register forms a cash register.

25 The chief feature of the invention consists in the construction of the drawer latch and the provision of an adjustable rigid lever extension.

The full nature of the invention will be understood from the accompanying drawings and the following description and claims:

30 In the drawings, Fig. 1 is a perspective view of a register, a cash drawer and cabinet therefor supporting said register. Fig. 2 is an enlarged side elevational view of the preferred form of the invention, part of the cabinet and drawer being shown in section to illustrate other parts in detail, said construction being shown in the latched position. Fig. 3 is a similar view of the same parts illustrating them in the released or 35 actuated position. Fig. 4 is an enlarged side elevational view of a portion of the actuating mechanism of the latch and diagrammatic outlines of the limit of movement or lower limiting position of the respective operating elements of substantially all commercial types of registers. Fig. 5 is a side elevational view of a modified form of the invention. Fig. 6 is an end elevational view of the same.

40 In the drawings 10 indicates a cabinet having a top 11 and a drawer 12. The top 11 is of suitable dimensions so as to support any one of a number of substantially all of the present models of commercial registers herein indicated by the numeral 13 and hav-

ing an operating shaft 14 actuatable by a handle 15.

The register is entirely detachable from the cash drawer cabinet, and is merely positionable thereon. If desired, however, it 60 may be attached to the drawer, but the weight of the machine generally is sufficient to maintain it in the desired position.

65 The drawer 12 includes a back portion 16, and upon the outside thereof, there is supported and secured a coiled spring 17 which is adapted to have its free end bear upon a bearing plate 18 secured to the back of the cabinet. Projecting into the drawer portion, as shown clearly in Fig. 2, there is a 70 lever latch 19, the free end 20 of which is adapted to abut the back 16 of the drawer and prevent outward movement of the drawer under the influence of the spring 17 when the lever latch is tilted upon its pivot 75 21 in opposition to the spring 20. The spring 20 is suitably secured in a recess 21 formed in the top 11 and normally tends to force the lever latch 19 into the latching position.

80 The lever latch 19 includes an offset portion 22, and said offset portion adjustably but rigidly supports an extension arm 23 including the offset bearing plate 24 engageable by the handle 15 of the register for tilting the lever 19 upon its pivot. As 85 shown clearly in Figs. 2 and 3, the top 11 is apertured as at 25 and the offset or lateral portion 22 extends through said opening or aperture. Closing said opening is a pivot 90 supporting plate 26 including the pivot 27 adapted to pivotally support the lever 19. Herein the pivot supporting plate is shown providing a pivot above the top 11. The lever 19 is extended beyond the offset portion 95 and terminates in a support 29 which includes an elongated slot 28. The free end of the lever extension 29 indicated by the numeral 30 is suitably housed by the housing 31 suitably secured to the top 11 of the cabinet. The housing 31 limits movement of 100 the lever in both directions, and particularly in the latching direction in opposition to the spring 20.

105 The bracket 32 is provided with a pair of lateral projections 33 which are receivable by the slot 28 in the extension 29 of the lever 19. The bracket 32 is provided upon the side opposite from said extensions 33 with a ledge 34. A nut or flat headed bolt is adapted to bear against said ledge 34 and 110

limit the turning movement but permit sliding movement of a bolt 35 which is slideable in the slot defined by the four walls including the two lateral projections 32 and the 5 two parallel walls of the slot 28 included between said projections. The bolt 35 is positioned in an elongated longitudinally extending slot 36 of the extension or arm 23. Also positioned in the slot 36 of the extension or arm 23 is a similar securing construction 37 which is associated with the bracket member 32. The foregoing arrangement provides for radial adjustment of the arm 23 as well as the angular adjustment 10 thereof with respect to the bracket 32 and the bracket 32 is also longitudinally adjustable upon the extension 29 and is prevented from turning movement with respect thereto by means of the angular projections 33. 15 Universal adjustability of the bearing portion 24 carried by the arm 23 is thus obtainable so that the external operating member or handle of any one or substantially all of the commercial registers can engage said 20 projection and through the adjustable extension or arm 23, trip or tilt the latch lever 19 out of latching position, thereby releasing the cash drawer 12.

In Figs. 5 and 6, there is illustrated a 30 modified form of the invention. In this form of the invention the aperture 25 of the top 11 is not closed by the pivotal support, but herein the pivotal support 127 is provided by a suitable bracket 126 suitably secured to the under face of the top 11. The latching lever 119 carries an offset or lateral extension 122 that projects upwardly through the aperture 125 of the top 11. Said extension terminates in an arcuate, and herein 35 in circular radially corrugated portion 129. Said radially corrugated portion is provided with a central aperture, and associated therewith is a bracket member 132 having a similar face whereby radial adjustment is secured through the medium of the bolt 135 with which is associated a wing nut as shown. The bracket 132 also supports a bolt 137. The arm or extension 123 is provided with an elongated longitudinally extending 40 slot 136, and said elongated slot is adapted to receive the bolts 135 and 137 whereby the arm 123 may be adjusted longitudinally with respect to the bracket 132. Said bracket 132 includes a transverse lug 133 45 receivable by the slot 136 and the foregoing arrangement likewise provides for substantially universal adjustability.

While the invention has been described in great detail in the foregoing specifications, 50 it is to be understood that various modifications thereof will readily suggest themselves to those skilled in the art to which the invention applies in addition to those herein illustrated, as well as suggested, and all of 55 said modifications are considered to be with-

in the broad purview of the invention, reference being had to the appended claims, for the broad idea of the invention consists in the rigid, adjustable extension for a latching lever controlling a cash drawer contained within a cabinet adapted to support any one of a number of commercial registers, the exterior operating element of which is adapted to engage the rigid adjustable extension and simultaneously release the 70 drawer and operate the register, thereby providing that a single model cash drawer cabinet is universally adaptable to any commercial register for transforming any register and a cash drawer into a cash register 75 at but a relatively small additional cost.

The invention claimed is:

1. The combination with a register having an operating element, and a cabinet stand therefor and having a drawer therein and 80 including an apertured top, of a control for said drawer including a lever pivotally supported by said top and extending through the aperture thereof and movable therein, and an extension rigidly but adjustably connected to said lever for universal adjustability, whereby the operating elements of a plurality of dissimilar registers are adapted to be interchangeably engaged thereby for 85 releasing the drawer.

2. The combination with a register having an operating element and a cabinet stand therefor and having a drawer therein and including an apertured top, of a control for said drawer including a lever pivotally supported above and by the top, and extending through the aperture thereof and movable therein, and an extension rigidly but adjustably connected to said lever for universal adjustability, whereby the operating elements of a plurality of dissimilar registers are adapted to be interchangeably engaged thereby for releasing the drawer.

3. The combination with a register having an operating element, and a cabinet stand therefor and having a drawer therein and including an apertured top, of a control for said drawer including a lever extending through the aperture thereof and movable therein, a bracket closing the aperture and pivotally supporting the lever, and an extension rigidly but adjustably connected to said lever for universal adjustability, whereby the operating elements of a plurality of dissimilar registers are adapted to be interchangeably engaged thereby for releasing the drawer.

4. The combination with a register having an operating element, and a cabinet stand therefor and having a drawer therein and including an apertured top, of a control for said drawer including a lever pivotally supported by said top and having an offset portion extending through the aperture and movable therein, and an extension rigidly 120

but adjustably connected to said lever for universal adjustability, whereby the operating elements of a plurality of dissimilar registers are adapted to be interchangeably engaged thereby for releasing the drawer.

5. The combination with a register having an operating element, and a cabinet stand therefor and having a drawer therein and including an apertured top, of a control for 10 said drawer including a lever pivotally supported above and by the top and having an

offset portion extending through the aperture and movable therein, and an extension rigidly but adjustably connected to said lever for universal adjustability, whereby 15 the operating elements, of a plurality of dissimilar registers are adapted to be interchangeably engaged thereby for releasing the drawer.

In witness whereof, I have hereunto af- 20 fixed my signature.

JOSEPH RALPH SHOWERS.
